UNITED STATES PATENT OFFICE.

HOMER F. MARSHALL, OF NORTH ADAMS, MASSACHUSETTS.

PICKER-STICK FOR LOOMS.

1,352,297.

Specification of Letters Patent. Patented Sept. 7, 1920.

Application filed November 1, 1919. Serial No. 334,942.

To all whom it may concern:

Be it known that I, HOMER F. MARSHALL, a citizen of the United States, residing at North Adams, in the county of Berkshire and State of Massachusetts, have invented new and useful Improvements in Picker-Sticks for Looms, of which the following is a specification.

The general object of my present sole invention is the provision of a picker stick of durable construction that will meet all of the practical requirements of a picker stick, and be adapted to be operated in the ordinary well known manner.

To the attainment of the foregoing, the invention consists in the embodiment as hereinafter described and definitely claimed.

In the accompanying drawings, hereby made a part hereof:

Figure 1 is a perspective of the picker stick constituting the best practical embodiment of my invention that I have as yet devised.

Fig. 2 is a full longitudinal section of the same.

Fig. 3 is an enlarged detail longitudinal section taken in a plane at right angles to Fig. 2 and illustrating the socketing and fastening of the breakable wooden portion of the stick in the metallic holder for said portion.

Similar numerals of reference designate corresponding parts in all of the views of the drawings.

As is well known to those skilled in the art, it is desirable under some conditions for a picker stick to break, and therefore my invention contemplates the employment in my novel stick of a comparatively short upper wooden section 1. It will be appreciated, however, that the breaking of the section 1 will not entail serious loss either of time or material, inasmuch as according to my invention the said section 1 is adapted to be expeditiously and easily removed, and as readily replaced with a new section without the employment of skilled labor.

In addition to the section 1, my novel picker-stick comprises a metallic holder 2 for the section 1; the said holder 2 being tubular so as to combine the necessary strength and resiliency required in picker sticks. The holder 2 comprises a lower

major portion 3, of circular form and comparatively large size in cross-section, and an upper socket portion 4; the latter being, by preference, of rectangular form in cross-section so as to snugly receive and hug and strongly hold the lower portion of the wooden section 1. As shown in Fig. 3, the lower end of the wood section 1 is opposed to shoulders 5 in the holder, which shoulders constitute a stop for the wooden section. Any suitable means may be employed to fasten the wooden section 1 in the socket portion 4, though I prefer to employ for the purpose the removable bolt 6, equipped with a nut 7.

At a point slightly below the socket portion 4, the holder portion 3 is provided with a vertical series of threaded apertures 8; this provision being made for the adjustable connection through the medium of a screw (not shown) of a sweep-stick strap, (also not shown).

Also comprised in my novel stick is a rocker-bearing 9, preferably of cast metal, and having a cylindrical terminal portion 10 disposed in and brazed to or otherwise fixedly associated with the holder portion 3.

My novel holder 2 is preferably formed of steel, and is practically unbreakable. It is also adapted to withstand the wear and strains to which picker sticks are ordinarily subjected, but notwithstanding this, it is light in weight and at the same time is possessed of sufficient resiliency to render the picker stick as a whole sufficiently springy, as is desirable. It will also be appreciated that the wooden section 1 of the stick is adapted to break under certain conditions, and thereby avert damage to more important parts of a loom, but this breakage will not entail serious loss, inasmuch as the section 1 is but a short length of wood, and it is my purpose to market corresponding short sections, so that when one of my improved picker sticks is incapacitated by the breakage of the wooden section 1 thereof, the said section may be quickly and conveniently removed and replaced with a new section. It will be further noticed, however, in this connection that the socketing of the lower portion of the wooden section 1 in the holder 2—*i. e.*, the arrangement of the base of the wooden section 1 in a pocket or socket

of the holder 2, enables the said holder 2 to reinforce and to lend increased strength to the section 1, so that while the resiliency of the stick throughout is preserved, the liability of the section 1 breaking under slight strains is reduced to a minimum.

In addition to the practical advantages hereinbefore ascribed to my novel picker stick, it will be manifest that the stick is capable of being installed quickly with the same facility as an ordinary picker stick, and is adapted to be operated in the same manner and by the same means as an ordinary picker stick.

Having described my invention, what I

claim and desire to secure by Letters-Patent, is:

As a new and useful article of manufacture, a metallic picker stick holder for looms comprising a lower tubular portion 20 and an upper socket or pocket portion of rectangular form in cross-section to receive and surround and reinforce the lower portion of a wooden picker stick section, and a rocker bearing having a cylindrical terminal portion disposed in and brazed to the lower end of the tubular portion of the holder.

In testimony whereof I affix my signature.

HOMER F. MARSHALL.
